UNITED STATES PATENT OFFICE.

SAMUEL B. FREDERICK, OF DETROIT, MICHIGAN.

BURNISHING-WHEEL.

1,266,932.

Specification of Letters Patent. Patented May 21, 1918.

Application filed February 4, 1918. Serial No. 215,376.

To all whom it may concern:

Be it known that I, SAMUEL B. FREDERICK, of 237 Griswold street, in the city of Detroit, county of Wayne, State of Michigan, 5 have invented certain new and useful Improvements in Burnishing-Wheels, of which the following is a specification.

My invention relates to burnishing wheels and bands therefor to be used in burnishing 10 leather boots and shoes.

The object of my invention is to provide a burnishing band shaped to conform to the shape of the ordinary burnishing wheel, adapted to be readily inserted over or removed from said wheel without removing 15 the wheel from the shaft on which it is mounted.

A further object of my invention is to provide a retaining plate to securely hold 20 said band to the burnishing wheel and which may be sprung over the shaft into operative position.

Of the accompanying drawings which form a part of this specification; Figure 1 25 represents a plan view of my burnishing band and retaining plate constructed in accordance with my invention, a portion of the retaining plate being cut away to disclose the tongues of the burnishing band. Fig. 2 represents a section on line 2—2 of 30 Fig. 1. Fig. 3 represents a cross section of my retaining plate showing the edge turned in to form a rim. Fig. 4 represents a plan view of a burnishing band constructed in 35 accordance with my invention, the burnishing band being flat and ready to be molded to conform to the shape of a burnishing wheel upon which it is to be used.

Similar reference characters indicate 40 similar parts in all figures.

In constructing my invention I take a band of leather 5 corresponding in length to slightly more than the circumference of the burnishing wheel upon which it is to 45 be used, and notch the same on either edge to form tongues 6 as shown in Fig. 4. I cause the tongues 6 to assume a position at right angles to the burnishing surface 7 of the band 5, by bending them at the base in 50 a mold or otherwise. The nature of leather is such that it may be molded into almost any desired shape, and hence after notching the band as shown in Fig. 4, I mold it into

circular form so as to make it conform to the shape of the burnishing wheel. There 55 is a lap-over 8 where the ends 9 of the band unite. The burnishing band 5 is placed around the wheel 10 overlapping at 8 and uniting at 9, the tongues 6 standing at right angles to the burnishing surface 7 of the 60 band 5.

To secure the band 5 to the burnishing wheel 10 I employ retaining plates of sheet spring-steel 11 which are cut through at 12. The retaining plates 11 are turned in on 65 the edges forming a sharp rim 13.

I apply my burnishing band to the burnishing wheel 10, which is mounted on a sleeve 14 adapted to be set on a shaft 15, by placing the band around the wheel and uniting its ends as shown in Fig. 1. One end of the sleeve 14 is provided with a shoulder 16 and the other end is threaded as shown in Fig. 2. To place the retaining plates 11 in position I drive the burnishing wheel 75 away from the shoulder of the sleeve 14, spring one of the retaining plates apart at 12, insert the plate over the sleeve and between the shoulder of the sleeve and the burnishing wheel. The burnishing wheel 80 and retaining plate 11 is then driven back against the shoulder of the sleeve 14. The other retaining plate is similarly inserted over the other end of the sleeve on the opposite side of said wheel and held in place by 85 a washer 17. The threaded end of the sleeve 14 is provided with a spanner-nut by which the assembled parts are drawn together thus forcing the rim of the retaining plates 11 90 tightly against the tongues of the band 5 and securely holding it in place and ready for use in burnishing.

Having thus fully described my invention, what I claim is:

In a burnishing band holder, the combination of a burnishing wheel, a leather band having its edges notched to form tongues, said tongues turned down at right angles to the burnishing surface of said band, retaining plates cut through at one point and 95 having their edges turned in to form a rim 100 and means for pressing said retaining plates against said tongues.

In testimony whereof I have signed this specification this 30th day of Jan., 1918.

SAMUEL B. FREDERICK.
